US00D626397S

(12) **United States Design Patent**
Smith et al.

(10) **Patent No.:** US D626,397 S
(45) **Date of Patent:** ** Nov. 2, 2010

(54) **ABRASIVE SHARPENER**

(75) Inventors: **Richard S. Smith**, Hot Spring, AR (US);
Louis Chalfant, Hot Springs, AR (US)

(73) Assignee: **Smith Abrasives, Inc.**, Hot Springs, AR (US)

(**) Term: **14 Years**

(21) Appl. No.: **29/311,262**

(22) Filed: **Feb. 3, 2009**

(51) LOC (9) Cl. **08-05**

(52) U.S. Cl. **D8/93**

(58) **Field of Classification Search** D8/63,
D8/90-94; 76/82, 84, 86-89; 451/552, 555-558
See application file for complete search history.

(57) **CLAIM**

The design for an abrasive sharpener, as shown and described.

DESCRIPTION

FIG. 1 is a front perspective view of the design for an abrasive sharpener of the invention;

FIG. 2 is the bottom plan view of the abrasive sharpener of FIG. 1;

FIG. 3 is top plan view of the abrasive sharpener of FIG. 1;

FIG. 4 is a front elevational view of the abrasive sharpener of FIG. 1;

FIG. 5 is a back elevational view of the abrasive sharpener of FIG. 1;

FIG. 6 is a right end elevational view of the abrasive sharpener of FIG. 1; and,

FIG. 7 is a left end elevational view of the abrasive sharpener of FIG. 1.
